(57) **CLAIM**

The ornamental design for a hand wheel, as shown and described.

DESCRIPTION

FIG. 1 is a front, right side perspective view of the hand wheel showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a cross-sectional view along the lines **8-8** in FIG. 6.

The broken lines in FIGS. 1-8 are for the purpose of illustrating environment, and form no part of the claimed design.
